UNITED STATES PATENT OFFICE.

ABRAM REESE, OF PITTSBURG, PENNSYLVANIA, ASSIGNOR TO C. L. MAGEE,
ROBERT PITCAIRN, AND C. McF. REED, ALL OF SAME PLACE.

SAFETY CAR-STOVE.

SPECIFICATION forming part of Letters Patent No. 398,800, dated February 26, 1889.

Application filed May 13, 1887. Serial No. 238,033. (No model.)

To all whom it may concern:

Be it known that I, ABRAM REESE, of Pittsburgh, in the county of Allegheny and State of Pennsylvania, have invented a new and useful Improvement in Safety Car-Stoves; and I do hereby declare the following to be a full, clear, and exact description thereof.

My invention relates to the stoves employed in railroad-cars for heating purposes, its object being to improve the construction of the safety car-stove heretofore patented by me on September 16, 1873, No. 142,867, and December 19, 1882, No. 269,324. In these car-stoves as covered by my previous patents a water-reservoir is arranged above the stove, this reservoir communicating by a valve with the fire-pot of the stove, and the valve being held closed by a cord which extends to the top of the car, to the side and end walls thereof, to the platform, and is connected with suitable tripping apparatus located in such position that it would be operated in case the car was derailed, and the apparatus was so arranged that in case of accidents—by a collapse of the car, the breaking of the platform, or the derailment—this cord would be slackened and the valve would be opened by a spring, so as to permit the water from the reservoir to pass down and flood the fire-box and extinguish the fire therein, the apparatus being so arranged that in case of accident the fire would be extinguished in this manner before the car could turn over, and consequently all danger from fires ignited by the stove located within the car was overcome.

My invention consists in certain improvements and combinations of parts, all of which will be fully hereinafter described.

To enable others skilled in the art to employ my invention, I will describe the same more fully, referring to the accompanying drawings, in which—

Figure 1 is a longitudinal central section of a car-stove and the end of the car, illustrating my invention; and Figs. 2 and 3 are detailed views illustrating the operation of the valve apparatus.

Like letters of reference indicate like parts in each.

50 The car *a* is of the usual or any approved

construction, having the roof *b*, the end walls, *c*, the bed or floor *d*, and the platform *d'*. Resting on the floor *d* is the car-stove *e*, which can be made of any approved form, this car-stove having the fire-box *e'* and the smoke-flue *e''*, leading from the upper part thereof to one side of the stove and thence upwardly through the roof *b*.

Above the top plate, *e''*, of the stove is the chamber *f*, which extends over the entire top surface of the stove, except at the center thereof, where the valve is located, and this chamber *f* is packed with asbestos or other suitable non-conducting material, the non-conducting material being confined between the top plate of the stove, the bottom plate, *b'*, of the water-reservoir *g*, and the outer wall, *f'*, and inner wall, *f''*, said inner wall forming the central valve-chamber of the apparatus.

The water-reservoir *g* extends above the stove any desired distance, so as to hold a sufficient body of water for extinguishing the fire, and is provided with any suitable filling-opening, as at *g'*. Located within this reservoir *g* and the valve-chamber *h* is the valve *i*, apparatus, which consists of the valve *i*, fitting within a seat, *k*, in the bottom-plate, *b'*, of the reservoir, and guided in its movement by the valve-stem *i'*, which passes through the bracket *h'* within the valve-chamber *h*, and the bracket *l* within the reservoir. This valve *i* is formed of asbestos, compressed to shape, or similar non-conducting material, which will prevent the passage of heat from the fire-box to the reservoir, and at the same time, as it is not liable to rust or disintegrate under the action of the water, is not soluble to stick in its valve-seat as the ordinary metal valve.

The top plate, *e''*, of the stove, which forms the base of the valve-chamber *h*, is perforated with a series of holes, which are preferably formed divergent, as described in Letters Patent No. 269,324, above referred to, so as to spread the water which passes from the reservoir into the valve-chamber, and thence through the perforations into the fire-box. The bracket *l* is provided with the arms *l'*, in which the lever *m* is pivoted, this lever being connected to the valve-stem *i'* by means of

the sliding joint, as shown particularly in Figs. 2 and 3, and the lever having hung to its opposite end the weight *n*, so that as soon as the cord is released the weight will drop 5 and draw up with it the valve-stem *i'*, so raising the valve *i* from its seat and permitting the passage of the water from the reservoir into the fire-box *e'* of the stove. As, however, the valve might stick slightly within its seat, 10 by means of the sliding joint *p*, formed between the lever and valve stem, I am enabled to impart a jar to the valve-stem and thus insure the opening of the valve.

The construction of the sliding connection 15 between the valve-stem and lever is particularly shown in Figs. 2 and 3, the valve-stem having the lugs or pins *r*, which extend into the slots *r'*, formed in the sleeve or plates *s*, this sleeve or like plates being pivoted to the 20 lever *m*, and when the valve is closed the extension on the cord forcing the lever down, so that the upper ends of the slots *r'* press against the lugs *r* and force the valve to its seat; but as soon as the cord is released in 25 any way, the weight *n* will draw down the lever *m*, and the slots *r'* slide over the lugs *r*, until the lugs are caught by the bases of the slots, thus imparting a jar to the valve and insuring the opening thereof. The cord *t* 30 passes upwardly through the reservoir and over the pulley *b²*, attached to the roof *b* of the car, thence over the pulley attached to the end wall thereof, and thence under the car, to be connected to the end platform and 35 to the end of the lever apparatus, as described in Letters Patent No. 269,324.

The operation of my improved stove is as follows: The valve is closed downwardly 40 against its seat by the tension on the wire cord or chain, as described in my previous Letters Patent, and the reservoir *g* is filled with water or other suitable liquid for extinguishing the fire, and the apparatus remains in this condition until through some 45 accident the cord is loosened, either by the caving in of the roof or the end walls of the car or crushing of the platform by the derailment of the car, when this cord is, of course, slackened, and as soon as the cord becomes slackened through any of these causes 50 the weight *n* draws down the outer end of the lever *m*, which in turn draws up the valve-stem *i*, imparting a jar thereto, as described, and so causing the opening of the valve, and 55 the rod then passes from the reservoir to the

fire-box, being spread over the body of the ignited fuel therein and quickly extinguishing the same, so that the fire is entirely extinguished before the stove could be turned over or broken so that it would be liable to 60 ignite the body of the car. As the valve apparatus is operated by a weight as contradistinguished from a spring, it is evident that the apparatus is always in condition for operation, and the objection heretofore found in 65 the employment of a spring for opening the valve, on account of the spring losing its temper or tension on account of the long exposure of the heated water, is entirely overcome. At the same time by means of the 70 joints between the valve-stem and lever I am enabled to impart a jar to the valve and insure its being opened. The body of asbestos or similar non-conducting material between the stove and water-reservoir prevents the 75 passage of any large amount of heat from the stove to the reservoir, and so reduces to a minimum the evaporation of the water within the reservoir, and the passage of any great body of heat through the valve-chamber is 80 also prevented by the employment of the asbestos valve, which prevents to a great extent the passage of heat through the upper part of the valve-chamber, and at the same time prevents the rusting and sticking of the 85 valve which was found an objection in the ordinary metal valves.

What I claim as my invention, and desire to secure by Letters Patent, is—

1. In safety car-stoves, the combination of 90 the stove, the water-reservoir located above the stove, the valve closing communication between said reservoir and stove, the operating-lever, and a sliding joint connecting the valve and lever, substantially as and for the 95 purposes set forth.

2. In safety car-stoves, the combination of 100 the stove, the reservoir located above the stove, the valve closing communication between them, the lever *m*, connected to the valve by a sliding joint, and the weight *n* for operating the lever, substantially as and for the purposes set forth.

In testimony whereof I, the said ABRAM REESE, have hereunto set my hand.

ABRAM REESE.
